ELECTRIC SOLDERING IRON

Julius Schubert, Long Island City, N. Y., assignor
or to Steiner Bros. Inc., Long Island City, N. Y.,
a corporation of New York

Application November 4, 1935, Serial No. 48,253

1 Claim. (Cl. 219—26)

This invention relates to electric soldering irons and, among other objects, aims to provide a relatively simple, rugged, reliable and cheap tool of this type adapted to be heated almost instantaneously. The main idea is to provide an improved simple tool that can be used with a small transformer and connected to an ordinary lamp socket or source of alternating current at the usual voltage or to any source of low voltage alternating or direct current.

Other aims and advantages of the invention will appear in the specification, when considered in connection with the accompanying drawing, wherein:

15 Fig. 1 is a central sectional view of a soldering tool adapted to be used with a separate transformer when supplied with alternating current at the usual voltage;

20 Fig. 2 is a similar view of a modified form of the tool having a transformer mounted in the handle;

25 Fig. 3 is a sectional view taken on the line 3—3 of Fig. 2; and

30 Fig. 4 is a fragmentary sectional view showing how the tool in Fig. 2 may be employed for welding and brazing.

Referring particularly to the drawing, the type of tool shown in Fig. 1 is designed to be used with a small step-down transformer when connected to 35 a source of alternating current at, say, 110 volts, or it may be connected directly to an automobile storage battery supplying, say, 6 to 12 volts. This type of tool is well adapted for use in factories, shops, laboratories, households and on farms for all kinds of soldering.

Herein, the tool has a hollow handle 10 conveniently made of wood or other suitable material. A metal tube 11 is removably secured in the 40 lower end of the handle by means of a screw 12 shown as projecting through it and to prevent the tube from burning the handle, it is insulated therefrom by a short tubular piece of heat insulating material 13, such as asbestos and mica. The lower end of the tube is screw threaded internally to receive a hollow soldering tip 14.

In this instance, electrical conduits 15 and 16 shown as leading from the low side of a transformer 17 enter the upper end of the handle 10, 45 one conductor being connected to the upper end of a slidible metal conductor 18 in the form of a small rod projecting into the tube 11 to a point near the lower end; while the other conductor is connected to the tube 11, whereby the circuit may 50 be completed through a carbon electrode 19 seated

in the tip to heat the carbon and transmit heat to the tip.

In this example, the lower end of the conductor rod 18 has a split socket to receive a small extension 20 which is adapted to be pushed into contact 5 with the upper end of the carbon electrode. Extensions of different lengths may be used to change the effective length of the rod.

To insulate the conductor rod 18 from the tube 11, there is shown a porcelain sleeve 21 closely fitted in the tube. The upper end of the sleeve is cut away on one side so that it will pass the screw 12 and provide a stop shoulder 22 to limit its movement into the handle. The lower end of the porcelain sleeve serves as a stop for the carbon electrode 19 so that when the rod is withdrawn from contact with the electrode, the electrode will not follow it into the sleeve.

The conductor rod 18 is adapted to be manipulated by a switch button 23 having a stem 24 projecting through an elongated slot 25 in the handle. This button may be made of heat insulating material and is preferably connected to a screw 26 which binds the terminal of conductor 15 to the upper end of the rod 18. The rod is normally urged upwardly out of engagement with the carbon electrode by means of expansion spring 27 between the upper end of the porcelain sleeve and the stem 24 of the push-button. Contact may be made by simply pushing on the button 23 until the 30 extension 24 strikes the electrode and the contact is broken when the button is released. The tip 14 is shown as having a peep opening 28 through which the carbon electrode may be observed. When the current is turned on by making the contact, the electrode will be heated almost instantaneously and will glow through the peephole.

In Fig. 2, there is shown a tool in which a small transformer is mounted in the handle. This type of tool is adapted to be used by tinners and plumbers and other artisans who require portable tools of this type. In this example, the conductor rod 18' is always held in contact with the carbon electrode 19' by a compression spring 30 electrically connecting one terminal of the transformer with the rod, the other terminal of the transformer being connected to the tube 11' by a conductor 31. The transformer is so designed as to form a part of the tool handle, and the upper end 32 provides a hand grip through which the conductors 15' and 16' project to connect to the high side of the transformer. In this case, the current is controlled by an ordinary switch 33 in the handle. This arrangement permits the handle, which may 45 be of any suitable design, and the soldering tool to 50 55

be attached to the opposite ends of the transformer housing. The tool is shown as being secured to an annular flange 34 on the transformer housing, a hollow extension 35 being connected to said flange. The hand grip portion of the handle may be secured in like manner to the upper end of the transformer housing.

This type of tool is ready for instant use when connected to alternating circuits. It is not necessary for the artisan to carry a separate transformer. It may be plugged into any convenient outlet for immediate use.

In Fig. 4, the tool shown in Fig. 2 is slightly modified for welding and brazing. In this instance, the tip 14' and the short extension 20' are removed and replaced by a screw bushing 40 and a long extension 41, respectively. The bushing is made of insulating material and serves to hold the porcelain sleeve 21' in place. The extension 41 has a split socket 42 to receive a carbon electrode 43. A clip 44 is secured to the tube 11' and a conductor 45 connects it to the work so that the circuit is completed through the carbon electrode and the work, back through the tube 11'. Thus, the tool may be used for soldering, welding or brazing.

From the foregoing description, it will be seen that tools embodying this invention are very simple in design and can be made of standardized parts. They are easy to operate and will comply with all requirements of the underwritten

ers. The carbon electrodes are easy to replace by removing the soldering tip. The welding rod extension is interchangeable with the short conductor rod extension and may be applied very easily so that the tool may be used for brazing, welding or for cutting. The tool is always ready for instant use and will take the place of practically all other soldering irons and similar welding tools.

Obviously, the present invention is not restricted to the particular embodiment thereof herein shown and described. Moreover, it is not indispensable that all of the features of the invention be used conjointly, since they may be employed advantageously in various combinations and sub-combinations.

What is claimed is:

An electric soldering tool of the character described comprising, in combination, a handle; a step-down transformer associated with the handle; a switch in the transformer circuit; a metal tube connected to one terminal on the low voltage side of the transformer; a soldering tip on the metal tube; a carbon electrode in the soldering tip; a conductor mounted in and insulated from the tube; and a combined compression spring and conductor connecting the upper end of the rod to the low voltage side of the transformer to maintain said rod in contact with said electrode.

JULIUS SCHUBERT.
